UNITED STATES PATENT OFFICE.

SYLVESTER LIEBENTHAL, OF CLEVELAND, OHIO.

DESIGN FOR A BOTTLE.

No. 38,833.

Specification for Design.

Patented Sept. 24, 1907.

Application filed August 6, 1907. Serial No. 387,363. Term of patent 7 years.

To all whom it may concern:

Be it known that I, SYLVESTER LIEBENTHAL, a citizen of the United States, residing at Cleveland, in the county of Cuyahoga and State of Ohio, have invented a new, original, and ornamental Design for Bottles, set forth in the annexed specification.

The design is shown in the accompanying drawing.

I claim:

The ornamental design for a bottle, as shown.

SYLVESTER LIEBENTHAL.
